UNITED STATES PATENT OFFICE.

FRANK RYMARZ, OF SPRINGWELLS VILLAGE, MICHIGAN, ASSIGNOR OF ONE-THIRD TO
JULIAN WILODANSKI, OF DETROIT, MICHIGAN.

DOOR LOCK.

Application filed April 28, 1924. Serial No. 709,378.

To all whom it may concern:

Be it known that I, FRANK RYMARZ, a citizen of Poland, residing at Springwells Village, in the county of Wayne and State of Michigan, have invented certain new and useful Improvements in Door Locks, of which the following is a specification, reference being had therein to the accompanying drawings.

10 This invention relates to door locks, and my invention may be characterized in the following particulars.

First, a lock mechanism is provided wherein a novel form of key is employed for actuating the lock mechanism, the key being out of the ordinary for the reason that it includes a barrel having spring retracted members which are distended when the key is placed in use, otherwise the members are retained in the barrel and the configuration of the barrel is such as to require a circular key hole, in contradistinction to the usual shape of keyhole, and this alone prevents an ordinary key from being used to surreptitiously actuate the lock mechanism.

Second, the lock mechanism includes swingable keyhole plates or abutments which are adapted to be swung by actuation of a knob operated latch, and when the key is left in the lock one of the keyhole plates is held in position to guard the keyhole from the opposite side of the door from which the key is inserted, consequently if the door is locked from the inside and the key left in place it is impossible for another key to be inserted in the lock from the outside of the door. This is true in connection with either side of the door and is a further safeguard against the lock mechanism being tampered with in an endeavor to open the door.

Third, an arrangement of tumblers cooperates with the lock bolt in preventing the lock bolt from being forced by any instrument placed between the strike plate and the lock face plate of a door. This is another safety feature and all of these features have been embodied in my lock without sacrificing strength and durability or materially increasing the expense of manufacture.

The lock mechanism will be hereinafter specifically described and then claimed and

reference will now be had to the drawings, 55 whercin—

Figure 1 is a vertical longitudinal sectional view of the door lock showing the latch retracted and a key hole plate in position so that a key may retract the lock bolt;

Fig. 2 is a perspective view of the key;

Fig. 3 is a horizontal sectional view of a portion of a door and door jamb showing the lock in plan; 65

Fig. 4 is a front elevation of the lock bolt and its tumblers with a key in position to actuate such parts;

Fig. 5 is a front elevation of the lock with the side plate thereof removed showing the 70 lock bolt in a retracted position;

Fig. 6 is a vertical cross sectional view of the same;

Fig. 7 is a view similar to Fig. 5, showing the bolt in a distended position and a key 75 in the lock preparatory to retracting the bolt, and

Fig. 8 is a horizontal sectional view of the lock with the key therein.

In the drawing, the reference numeral 1 denotes a door frame or jamb provided with a strike plate 2 having a latch opening 3 and a bolt opening 4, said openings communicating with recesses 5 in the door frame or jamb adapted to provide clearance for the latch and bolt of my lock. 80

Reference numeral 6 denotes a lock casing set in a pocket or recess 7 provided therefor in the edge of a door 8, said lock casing having a face plate 9 by which it is secured to the door 8, and access is had to the casing by removing a detachable side plate 10 normally held on the lock casing by posts 11 and 12 and screws 13.

In the upper part of the casing 6 and extending into a latch opening 14 thereof is a latch 15 having a stem 16 slideable in guides 17 carried by the fixed side wall or plate of the lock casing. Encircling the stem 16 between the guides 17 and the latch 15 is a coiled expansion spring 18 which is adapted to hold the latch 15 normally distended and a yoke 19 of the latch stem normally against the guides 17. 85

Rotatable in the lock casing, at the yoke 19, is a barrel 20 carried by a knob spindle 21 extending through said barrel and by which spindle the latch is adapted to be

retracted when a door knob is turned in one direction or the other. On the barrel 20 are lugs 22 and 23 with the former engaging a pin 24 of the yoke 19 and the latter engaging the upper pivoted ends 25 of keyhole plates 26 and 27 which are suspended from a pin 28 on the yoke 19. If the knob spindle 21 is turned clockwise or counterclockwise the latch 15 will be retracted but in either instance one or the other of the keyhole plates 26 or 27 is adapted to be swung into an active position to guard or close the inner end of the circular keyhole 29 in the side plates or walls of the lock casing. This is brought about by providing the keyhole plates 26 and 27 with slots 30 for a fulcrum pin 31 of the lock casing and arranging the keyhole plates the reverse of each other, that is, with one of said keyhole plates adapted to swing away from the keyhole 29 at one side of the lock casing when the other keyhole plate is brought into active position to close the keyhole at the opposite side of the lock casing. This is best shown in Figs. 5 and 8 where the keyhole plate 26 closes the keyhole 29 at one side of the lock casing and the keyhole plate 27 is to one side of the keyhole 29 at the opposite side of the lock casing, thus permitting of the key being inserted in the lock casing to abut the keyhole plate 26. The keyhole plates have the action of pivoted shutters within the lock casing and by holding one of the shutters against movement the other is also held against actuation, as will hereinafter appear.

The lock casing 6 has studs 32 in the lower part thereof and slidably on said studs is a lock bolt 33 which extends into a bolt opening 34 in the face plate 9 of the lock casing.

The lock bolt 33 has a substantially oval shaped opening 35 and the upper wall of said opening has a key notch 36. Above and below the opening 35 are keeper lugs 37 extending into one or the other of two communicating seats 38 provided therefor in each tumbler 39, said tumblers being disposed parallel to the lock bolt 33 and pivotally supported on studs 40 carried by the lock casing. The tumblers 39 are spring pressed by flat springs 40 and 41, the former engaging the bottom wall of the lock casing 6 and the latter engaging the post 11, so that the tumblers will be pressed towards each other and normally in engagement with the keeper lugs 37. With the keeper lugs 37 in one set of the tumbler seats 38 the lock bolt 33 will be held in a retracted position, as shown in Fig. 5, and when in the other set of tumbler seats the lock bolt will be held in a distended position, as shown in Fig. 7. The tumblers 39 have the confronting edges thereof provided with cam surfaces 42 adapted to be engaged by a key.

The key comprises a barrel 43 and reciprocal in said barrel is a plunger 44 having a key handle 45 and a reduced portion 46, said reduced portion being encircled by a coiled expansion spring 47 seated on an annular shoulder 48 of the barrel, so that the expansive force of the spring will tend to force the plunger 44 out of the outer end of the barrel. On the inner end of the plunger are pivoted retractile members 49 having teeth 50 and shoulders 51. The retractile members 49 are disposed side by side on a common pivot 52 and one of said members has a stop lug 53 which will allow the members to be brought into parallelism for partial enclosure by the barrel 43, but prevent the members 44 from being spread other than in a defined way when the key is placed in the lock casing.

Considering the operation of the lock mechanism, and assuming that the lock bolt 33 is in a retracted position, as shown in Fig. 5, the door 8 can be opened and closed by using the latch 15 in the usual way, but each and every time the latch 15 is retracted, one or the other of the keyhole plates 26 or 27 is actuated. With the lock mechanism in the condition shown in Fig. 5, the plate 26 is in position to serve as an abutment for the key, when inserted in the keyhole 29, for instance at the inner side of the door. As the key encounters the plate 26 and is pushed inwardly the members 49 are spread apart to assume an opposed relation, somewhat like a cross head on the inner end of the key. The distension of the members 49 is caused by the key being forced inwardly against the keyhole plate 26 and by retaining pressure on the key and turning it in a clockwise direction, the shoulders 51 of the members 49 separate the tumblers 39 by engaging the cam surfaces 42. With the tumblers separated, as shown in Fig. 4, the tumbler seats 38 are moved away from the keeper lugs 37 and as the key is turned a tooth 50 thereof rides into the notch 36 and retracts the lock bolt 33. As this bolt is retracted the tumblers 39 shift towards each other and another set of the tumbler seats engage the lugs 37, thus locking the bolt in a retracted position.

If the key is left in the lock casing, as shown in Fig. 8, with the keyhole plate 27 engaging one of the members 49, the latch 15 cannot be retracted by turning the door knob, consequently the latch will cooperate with the bolt in securing the door against any surreptitious manipulation of the lock mechanism from the outer side of the door. The outer keyhole being closed by the plate 26 prevents a key or instrument from being inserted in the lock casing.

It is thought that the manner of distending the lock bolt by the key will be apparent without further description, and while in

the drawings there is illustrated a preferred embodiment of my invention, it is to be understood that the structural elements are susceptible to such variations and modifications as fall within the scope of the appended claims.

What I claim is:

1. A door lock comprising a casing having keyholes, keyhole plates supported in said casing and adapted to be shifted so that one of said plates closes one of said keyholes, a latch mechanism adapted to shift said keyhole plates, a bolt, and a key operable by engagement with one of said keyhole plates for shifting said bolt, said key including contractible members held in active positions by pressure of said key against said keyhole plate.
2. A door lock comprising a casing having keyholes, keyhole plates supported in said casing and adapted to be shifted so that one of said plates closes one of said key holes, a latch mechanism adapted to shift said keyhole plates, a bolt, spring pressed tumblers adapted to hold said bolt

in adjusted position, and a key operatable by engagement with one of said keyhole plates for shifting said bolt, said tumblers being retractile by said key.

3. In a lock mechanism having a bolt and tumblers normally securing said bolt, a casing for said bolt and tumblers, said casing having keyholes, plates supported in said casing with one of said plates at all times closing one of the keyholes against the insertion of a key, a key adapted to be inserted in the open keyhole and forcibly held against the plate closing the other keyhole, said key being adapted to operate said bolt and tumblers, and a latch mechanism articulated with said plates and adapted to shift said plates to open one keyhole and close the other.

In testimony whereof I affix my signature in the presence of two witnesses.

FRANK RYMARZ.
